UNITED STATES PATENT OFFICE.

GEORGE SCRIVER, OF CREEMORE, ONTARIO, CANADA, ASSIGNOR TO WILLIAM THOMAS MULLER, OF COLLINGWOOD, ONTARIO, CANADA.

AIR-PUMP.

1,271,232.

Specification of Letters Patent.

Patented July 2, 1918.

Application filed July 12, 1916. Serial No. 108,882.

To all whom it may concern:

Be it known that I, GEORGE SCRIVER, of the village of Creemore, in the county of Simcoe and Province of Ontario, Dominion of Canada, have invented certain new and useful Improvements in Air-Pumps; and I hereby declare that the following is a full, clear, and exact description of the same:

This invention relates to an air pump in which the pump cylinder is rockably mounted in a bearing bracket and the piston rod is knuckled to a pump handle fulcrumed to a bearing bracket, the rocking movement of the pump cylinder compensating for the changes in the position of the knuckle as the pump handle swings to and fro during the operation of the pump.

The invention further relates to certain novel features in the construction of the pump cylinder which may be briefly described as consisting of a cylinder casing, two cylinder heads located at opposite ends of the cylinder casing, and coupling bolts which hold the cylinder casing and heads in their assembled relation, each cylinder head having a valve-controlled air inlet, charging the cylinder when the piston is moving in one direction, and resisting the outlet of the air as it moves in the opposite direction, each cylinder head also having a back pressure valve-controlled air outlet, these air outlets being connected by a header fitted with a flexible air conduit, and with a gage for indicating the pressure therein.

35 In the drawings:—

Figure 1, is a vertical sectional view of the pump showing the construction and relation of the parts;

Fig. 2, is an end view of the pump cylinder and the bearing therefor;

Fig. 3, is a sectional elevation of the pump handle and bracket therefor;

Fig. 4, is a fragmentary view of the pump handle;

45 Fig. 4^a, is a fragmentary view of the pump handle taken at right angles to the plane shown in Fig. 4;

Fig. 5, is a fragmentary view of the pump handle shown in Figs. 4 and 4^a, showing a 50 modification of the handle grip.

Like characters of reference refer to like parts throughout the specification and drawings.

The pump consists essentially of a cylinder

comprising a cylinder casing *a*, cylinder heads *b* and *c* at the ends thereof coupled by bolts *d* which hold the cylinder casing and cylinder heads in their assembled relation, a piston *g* working within the cylinder, a piston rod *h* for the piston extending beyond the cylinder head *c*, and a pump handle *i* knuckled to the outer end of the piston rod *h*.

The cylinder head *b* is provided with trunnions *v* journaled in brackets *e*, preferably bolted or otherwise rigidly fastened to a relatively stationary base *f*, the cylinder rock ing or oscillating during the movement of the pump handle to compensate for the variation in the changes of location of the knuckle during the rocking of the pump handle on its fulcrum, as hereinafter described.

The pump handle *i*, as shown in Figs. 1 and 3, is fulcrumed between the arms *j* of the supporting bracket *j'*. This bracket *j'* is preferably bolted or otherwise rigidly fastened to the relatively stationary base *f*, and is so located that the knuckle of the pump handle is in correct axial alinement with the pump cylinder in all changes of position during the movement of the pump handle.

The lower end of the pump handle *i* is formed with a curved arm *i''* which enters between the forks *i³* of the piston rod *h*, and is connected therewith by a pin *i⁴*, the arm, forks, and pin, constituting the knuckle connection between the pump handle and the piston rod. The long arm of the pump handle consists of two parts *l*, *l'*, the part *l'* being separable from the part *l*. The parts *l*, *l'* are respectively provided with bolts *m*, *m'* and wing nuts *m''*, *m'*. The ends of the parts *l*, *l'* are slotted, the slots *m⁴*, *m⁵* receiving the bolts when the parts are assembled, this arrangement forming an easy method of assembling or separating the handle parts respectively for use or storage purposes.

In Fig. 5 the pump handle is formed with a looped handle grip *j³*, which is found to be a most convenient type by reason of the facility by which it can be seized and the natural action of the hand and arm during the operation of the pump handle.

In the operation of the pump, the handle is rocked upon its fulcrum, and during its movements, draws the piston rod out of, and then presses it into, the pump cylinder. Dur-

ing the movements of the handle, the knuckle joint changes its elevation, and this change in the elevation of the knuckle rocks the pump cylinder in its bearings in the bracket 5 *e*, without, however, altering the axial alignment of the knuckle, piston rod, piston and cylinder.

In the detail construction of the pump cylinder, as shown in Fig. 1, each cylinder 10 head is provided with a valve-controlled air inlet *o*, *o'* and a valve-controlled air outlet *p*, *p'*, the air outlets being connected by a header *q*, fitted with the flexible conduit *r*, and with an air gage *s*. During the operation 15 of the pump handle, the air is forced from the cylinder into the header and air conduit, the readmission of the air from the header into the cylinder being prevented by the back pressure valves *p''* for the outlets *p*, *p'*.

It is possible to make the bearing brackets *e* and *j* of a single casting or forging, the parts *e*, *f*, and *j* in that case being of a unitary character.

25 By means of a construction of this kind, it is possible to equip an automobile with a stationary pump and operate it with a minimum of power. It is also possible to place the pump within a pump box fastened to the 30 running board or some other convenient part of the automobile, where it will always

be available for use without disturbing the occupants of the vehicle.

Having thus fully described the nature of my invention, what I claim as new and desire to secure by Letters Patent, is:—

An air pump comprising a cylinder having valve-controlled air inlets and outlets, a piston operable within the cylinder, a piston rod for the piston extending through one of the cylinder heads and bifurcated at its outer end, trunnions for the other cylinder head, brackets in which said trunnions are journaled, a stationary base for the brackets, a pump handle formed with a curved arm, knuckled to the piston rod, and brackets secured to the base, to which the pump handle is fulcrumed above the point of attachment to the piston rod, the pump handle during its operation causing the reciprocating movement of the piston, and the rocking or oscillating movement of the cylinder, to compensate for the variation in changes of location of the knuckle during the rocking of the pump handle on its fulcrum.

Collingwood, May 10th, 1916.

GEORGE SCRIVER.
